United States Patent Office.

THOMAS BROWN, OF ALLEGHENY CITY, PENNSYLVANIA.

Letters Patent No. 79,200; dated June 23, 1868.

IMPROVEMENT IN HYDRANTS.

The Schedule referred to in these Letters Patent and making part of the same.

TO ALL WHOM IT MAY CONCERN:

Be it known that I, THOMAS BROWN, of Allegheny City, Allegheny county, and State of Pennsylvania, have invented a new and useful Improvement in Hydrants; and I hereby declare that the following is a full, clear, and exact description of the construction and operation of the same, reference being had to the annexed drawings, and to the letters of reference marked thereon.

The nature of my invention consists in providing the stem of stop-valves in hydrants with a screw or worm, and also furnishing the reservoir with a nut of the same pitch as the screwed stem, through which nut the stem works and rotates, a movable cap, through which the spout of the hydrant passes, an inclined slot or groove in the main column of the hydrant, through which the spout passes and travels, being used in combination with the ordinary valve, reservoir, inlet-pipe, supply-pipe, and spout, for the purpose of regulating the supply of water, the whole being constructed, arranged, and operating in the manner hereinafter described.

To enable others skilled in the art of constructing hydrants to make and use my invention, I will proceed to describe its construction and operation.

In the accompanying drawings—

Figure 1 represents a side elevation of my improvements in hydrants.

Figure 2 represents a front elevation of my improvement in hydrants.

Figure 3 represents a section of my improvement in hydrants.

Figure 4 represents an elevation of my improved valve, showing the screw or worm.

Figure 5 represents a section of the reservoir and inlet-pipe, showing the valve, screw, nut, and valve-seat.

Figure 6 represents the inclined slot or groove, near the top of main column.

Figure 7 represents a plan of reservoir, showing valve-seat.

In the accompanying drawings—

A represents the main column of an ordinary hydrant.

B represents the inclined slot or groove, in which the spout moves.

C represents the movable cap, in which I make a perforation equal to the diameter of the spout, which passes through it.

D represents the bent spout.

E represents the supply-pipe, connected with the bent spout D, by means of a female elbow, F, which supply-pipe E is furthermore connected with the stem G of the valve, by being screwed to it.

G represents the hollow stem of the valve H.

H represents the valve, with openings at the side, as at K.

J represents the worm or screw on the hollow valve-stem G of the valve H.

L represents the nut, in which the worm or screw J passes and revolves, which nut L is connected with the reservoir, by means of being screwed to it, as at N.

M represents the reservoir.

O represents the inlet-pipe, which is part of the reservoir M.

P represents the raised valve-seat, which is also part of the reservoir M.

Q represents the base, which is connected with the main column A by means of screws, and also attached to the reservoir M by means of the screw R and the nut S.

T represents a ring, of gum or leather, pressed into a dove-tailed recess at the bottom of valve H, which gum or leather bears light upon the raised valve-seat P, when the valve H is closed.

I propose, for the purpose of manufacture, making the main column A of wood, cast iron, or any other suitable material; the movable cap C of the same material; the spout D of cast or wrought iron, or malleable metal; the female elbow F of cast or wrought iron, or malleable metal; the supply-pipe E of wrought or cast iron; the base, Q, of wood or cast iron, and the remaining articles of brass, except the joint-ring T, which would be of gum or leather.

The form and mode of making the various parts of my improvement in hydrants, I leave to the taste, skill, and judgment of the mechanic.

The operation of working my improvement in hydrants is as follows, viz: By moving the bent spout D around a quarter of a revolution, which spout D moves the cap C, by passing through a hole in it, of the same diameter as the spout D, and the spout D moves along the inclined slot B of the main column A. The bent spout D, by the same operation, and at the same time moves around, in the same direction the supply-pipe E, as it is connected to the spout D by means of the female elbow F, and at the same time rotates the screwed hollow stem G of the valve H. As the supply-pipe E is connected with the stem G, by means of being screwed into it, as at I, and the worm or screw J on the hollow stem G of the valve H, working in the nut L, raises the valve H and the joint-ring T from the face of the valve-seat P, the water from the inlet-pipe O passes up through the valve-seat P into reservoir M, and through openings K in the valve H, through the hollow stem G, up through the supply-pipe E, and delivers itself from the spout D. When sufficient water is furnished, by turning the spout back again to its original position, it operates reversely, and brings the valve H and joint-ring T down upon the raised valve-seat P, and cuts off the supply.

When the supply of water is cut off, the spout D is over and in a direct line with inlet-pipe O.

When the supply of water is being delivered, the spout D is at right angles with the inlet-pipe O.

The inclination of the slot B is such as to allow the spout D to rise vertically the same distance as the valve H is lifted from its seat, when the spout is turned.

I do not claim operating a hydrant by the turning of the spout, such devices being heretofore in use; but, having thus described the nature, construction, and operation of my invention,

What I claim, and desire to secure by Letters Patent, is—

1. The spout D and pipe E, with the inclined slot B, and movable cap C, combined, arranged, and operating substantially as described.

2. The hollow valve H and hollow screwed stem G, with the nut L, pipe E, and spout D, combined, arranged, and operating as and for the purpose set forth.

THOS. BROWN.
